LOOSE-LEAF BINDER

James Cooper, Solvay, and Gerhard H. J. Baule,
Syracuse, N. Y., assignors to Hall & McChes-
ney, Inc., Syracuse, N. Y., a corporation of
New York

Original application February 23, 1937, Serial
No. 127,122. Divided and this application De-
cember 18, 1937, Serial No. 180,636

6 Claims. (Cl. 129—23)

This invention relates, in general, to loose-leaf binders and is directed more particularly to improvements in the structure operable to detachably lock the ends of the leaf impaling posts to the back member of the binder.

In our Patent No. 2,159,009, issued May 23, 1939, we have illustrated a loose-leaf binder in which the present invention is particularly applicable, the binder in that instance being of the full automatic type wherein after like ends of the posts have been detached from the back member they are automatically locked to the back member by simply closing the cover of the binder. The structure pertaining to the automatic mechanism of that binder forms no part of this invention, this present case constituting a division of the former application referred to and the particular post engaging structure herein claimed may be also employed in loose-leaf binders not embodying the full automatic feature.

The present invention has as an object a particularly simple and economical structure operable to securely lock the ends of the leaf impaling posts to the back member or housing carried thereby upon engagement of the housing with the ends of the posts.

The invention consists in the novel features and in the combinations and constructions herein-after set forth and claimed.

In describing this invention, reference is had to the accompanying drawings in which like characters designate corresponding parts in all the views.

Figure 1 is a plan view, partly in section, of a binder illustrating our invention and with the covers in flat open position.

Figure 2 is a cross sectional view of the binder shown in Figure 1 taken on substantially lines 2—2, Figure 1, illustrating one of the housings detached from the leaf impaling posts and the back member swung outwardly to provide for the reception or removal of the leaves.

Figure 3 is a plan view of a slide bar showing the post engaging members or locks and showing a modified form of slide actuating handle.

Figures 4 and 5 are sectional views of a housing and slide bar of the type shown in Figure 3 taken on substantially lines 4—4 and 5—5 respectively of Figure 3.

Figure 6 is a fragmentary lengthwise sectional view of the slide bar shown in Figure 3, taken substantially on lines 6—6, Figure 3.

The post engaging and locking mechanism herein particularly referred to may be advantageously used in any form of loose-leaf binder

wherein the ends of the leaf impaling posts are detachably secured to the back member.

As here shown, the back member consists of inner and outer plates 10, 11, secured together at their longitudinal edges. A suitable outer covering 12 of leather, or like material, is secured to the outer plate 11 and may be reinforced by an arcuate shaped piece of rawhide or other stiffening material 13 in the conventional manner. A cover 15 is hinged to each longitudinal edge of the back member on a pivot 16, and a lengthwise extending tubular housing 17 is also pivotally mounted to one or both edges of the back member on the cover pivot 16. The inner sides of the housings 17 are formed with apertures 18 to receive the ends of the posts 19. It is to be understood that a housing 17 may be pivotally secured along each edge of the back member, in which instance, the apertures 18 in each housing are arranged in alinement to effect the proper spacing of the posts 19, and the housings contain means operable to detachably secure the ends of the posts to the housings to in turn secure the posts to the back member of the binder with the posts extending transversely thereof and in spaced apart relation thereto.

The binder structure herein disclosed includes mechanism operable to effect engagement of the housings 17 with the ends of the posts 19 upon closing movement of the adjacent cover 15. That is, after one of the housings 17 has been detached from like ends of the posts and the back of the binder swung outwardly to permit removal and insertion of leaves, as illustrated in Figure 2, the back member is moved to vertical position and the housing moved into engagement with the ends of the posts automatically by simply closing the open cover. This mechanism is arranged between the plates 10, 11, and is connected to the housings 17 by means of links 20. This structure is claimed in our patent referred to and forms no part of this invention.

The mechanism for detachably securing the ends of the posts 19 in the housings 17 includes a slide bar 22 preferably of channel formation having a bottom wall 23 and side flanges 24. One end of the slide bar 22 extends outwardly through the end of the housing and is shaped to form an operating handle 25. The ends of the bottom wall and side flanges are formed to provide an end wall at the opposite end of the bar. The bar is slidably mounted in the housing with the bottom wall 23 overlying the inner side of the housing 17 in which the post receiving apertures 18 are formed, and a compression spring 26

- is inserted in the housing between the end thereof and the end wall of the slide bar to yieldingly position the slide bar with the handle 25 extending outwardly as shown in Figure 1. Outward movement of the bar 22 by spring 26 is limited by a rivet 27 extending through the housing. The bottom wall 23 of the bar is formed with a slot to receive the shank of the rivet and to permit sliding movement of the bar.
- 10 The bottom wall of the slide bar 22 is formed with a plurality of elongated openings, there being one of such openings for each post receiving aperture 18 in the housing. The slide bar 22 is provided with a post engaging member arranged in juxtaposition to each of the openings in the bar. Each post engaging member is provided with means arranged adjacent one end of each opening in the slide bar and is operable to detachably secure the posts to the bar and housing. The opposite end portion 29 of each of the elongated openings in the slide bar is of such dimension as to clear the ends of the posts when the bar 22 is moved axially inwardly. Opposite sides of the ends of the posts 19 are tapered as 15 at 31 and are provided with notches immediately below the tapered surfaces 31.
- Preferably, and as here shown in Fig. 4, the opposite or outer wall of the housing 17 is provided with apertures to receive the ends of the posts, whereby the posts are secured to the housing in a substantially rigid manner being supported by the walls of the apertures and by the post engaging members.
- 30 In Figures 3 to 6 inclusive, we illustrate a slide bar having individual post engaging members arranged at each of the elongated openings and which are conveniently installed in the bar and detachably secured thereto. These post engaging members 32 are formed of comparatively 35 thin spring material and are preferably channel shaped in cross section, as is the slide bar 22, and are of such width as to snugly fit between the side flanges 24 of the bar. The bottom wall of the post engaging members 32 is formed with an elongated opening substantially coextensive with the elongated openings in the slide bar. However, at one end of the opening flanges 33 extend inwardly and upwardly. The bottom wall of the slide bar is apertured in such 40 manner as to form flanges 34 which extend inwardly a short distance and serve to back up the flexible flanges 33 of the post engaging member. The opposite end portion 29 of the opening in the slide bar, is also formed with flanges 35 which do not extend inwardly any appreciable 45 distance, but are bent upwardly as indicated in Figures 3 and 5. The adjacent end portion of the opening in the post engaging member is of such dimension and width as to fit over the 50 upwardly extending flanges 35, and these flanges together with the flanges 34 are thus cooperable with opposite ends of the openings in said post engaging members to prevent relative axial movement between the same and the slide bar. The 55 depth of the side flanges of the post engaging members is such that the top edges thereof engage the inner surface of the opposite wall of the housing 17.
- 70 The outer end of the side flanges 24 of the bar shown in Figs. 3 and 6 terminate short of the end of the bottom wall 23, as at 40. The outer end of the bottom wall is formed with a slot 41 and an angle shaped lug 42 is struck up from the bottom wall 23 adjacent the ends 40 of the side walls.

In assembling the structure, the post engaging members 32 are inserted in the slide bar, it being understood that there is a post engaging member arranged at each opening in the slide bar. The compression spring 26 is then inserted 5 in the housing together with the slide bar 22. The slide bar 22 is pressed inwardly with a separate handle 44, the inner end of which engages the lug 42 and subsequently the top wall of the housing 17 is pressed downwardly to form a reduced end portion 45, see Figure 9. At this time, a rivet 46 is inserted through the top wall of the housing and through an elongated slot 47 formed in the handle 44. The bottom of the rivet is provided with a shank 48 which extends through 10 a hole in the bottom wall of the housing, and the shank is headed over to secure the rivet to the housing. The rivet 46 also acts as a stop to limit outward movement of the slide bar.

It will be observed that this structure is particularly economical both as to material and the consumption of time in forming and assembling the housing and post engaging structure. The slide bar may be formed of any suitable sheet metal material, it being necessary only to form 25 the post engaging members from the more expensive spring material. Also, the structure is particularly convenient to assemble and while the flanges 33 are extremely flexible and accordingly readily engage with the ends of the posts, 30 the structure is of comparatively great strength due to the fact that the flanges 33 are backed up or reinforced by the flanges 34 of the slide bar.

We have found, over an appreciable period of 35 time, that this post locking structure operates very efficiently and is exceptionally durable and generally more satisfactory than structures heretofore used which, in the main, consisted of the slide bar being formed with pintles which entered holes formed in the ends of the posts.

What we claim is:

1. A loose-leaf binder comprising a back member, a cover hinged to each edge of the back member, a plurality of leaf impaling posts extending transversely of the back member, a housing extending along one edge of the back member and being secured thereto and being provided with post receiving apertures, a slide bar mounted in the housing, said slide bar being channel shaped in cross section and being formed with elongated openings in the bottom wall thereof and having flanges extending inwardly from the side edges of said openings, post engaging members arranged in said bar and being formed with openings coextensive with the openings in said bar, the flanges of the slide bar being cooperable with said post engaging members to detachably secure the same to the slide bar, said post engaging members being formed with flexible post engaging flanges extending inwardly partially across one end of said openings and being operable upon engagement with the ends of the posts to lock the posts to the housing, and means operable to yieldingly urge said bar axially of the housing to normally position said post engaging flanges in register with the post receiving apertures of the housing.

2. A loose-leaf binder comprising a back member, a cover hinged to each edge of the back member, a plurality of leaf impaling posts extending transversely of the back member, a housing extending along one edge of the back member and being secured thereto and being provided with post receiving apertures, a slide bar 75
